UNITED STATES PATENT OFFICE

166,617

TOILET PAPER ROLL COVER

Helen D. McLellan and Sidney M. Boss, Chicago,
Ill., said Boss assignor to said McLellan

Application January 3, 1952, Serial No. 17,909

Term of patent 14 years

(Cl. D4—3)

To all whom it may concern:

Be it known that we, Helen D. McLellan and Sidney M. Boss, citizens of the United States residing at Chicago, in the county of Cook and State of Illinois, have invented a new, original, and ornamental Design for a Toilet Paper Roll Cover, of which the following is a specification, reference being had to the accompanying drawings, forming a part thereof:

Fig. 1 is a perspective view of a toilet paper roll cover showing our new design, taken from a point slightly above the top of the cover and from one corner thereof;

Fig. 2 is an end elevational view on a slightly smaller scale than Fig. 1;

Fig. 3 is a top plan view;

Fig. 4 is a front elevational view; and

Fig. 5 is a medial sectional view taken along the lines 5—5 of Fig. 4.

We claim:

The ornamental design for a toilet paper roll cover, substantially as shown.

HELEN D. MCLELLAN.
SIDNEY M. BOSS.
